METHOD AND MEANS OF BOILER CONTROL

Application filed May 2, 1927. Serial No. 188,103.

This invention relates to a method and means for regulating the quality of the steam generated and controlling the condition of the boiler water.

5 Boiler feed water or more particularly the make-up feed water contains mineral substances in solution. The evaporation of such feed water in boilers results in the accumulation of, or in other words, the concentration 10 of, these mineral substances in the water contained in the boiler. Since the amount of water contained by the boiler is kept fairly constant, the process of steaming comprises feeding water to the boiler continuously in 15 such quantities as will replace that which is changed to vapor and leaves the boiler as steam. As the steaming process is carried on, therefore, the mineral and other impurities of the feed water concentrate in the water 20 remaining in the boiler. Since the amount and kind of impurities concentrated in the boiler water have an effect upon the turbulence with which the water boils, it is known that as the concentration increases 25 the steam liberated tends to entrain greater quantities of finely divided boiler water. The more unevaporated boiler water there is mingled with the steam, the poorer is its 30 quality and for power purposes, the lower its efficiency.

It is known that higher steaming rates are accompanied by greater turbulence of the water in the boiler regardless of the presence of impurities. The turbulence is the least 35 with pure water and becomes worse with impure water usually reaching severe violence as the concentration of impurities becomes too great for the particular operating conditions.

40 In order to prevent boiler conditions that cause the generation of steam of low quality, or even priming during which slugs of water may be carried out of the boiler with the steam, it is common practice to reduce the 45 boiler water concentration at intervals. The usual practice is to draw off a quantity of water from the boiler and replace this with fresh feed water. This operation is spoken of as blow-down of the boiler and is usually done by hand once each shift or as frequently

as may be necessary to reduce turbulence within permissible limits.

Such manual blow-down of boilers usually is by routine and therefore, commonly results in either too little or too much boiler 55 water being removed for the actual operating conditions. The boiler is blown down a certain amount regardless of the steam output or the amount of feed water added and regardless of the particular steaming conditions. No attempt is made to regulate the amount of blow-down so that it will be proportionate to the amount of water evaporated, the rate of evaporation, or the quality 60 of the steam produced. In those instances 65 where the boiler blowdown is regulated in accordance with the amount of feed water admitted to the boiler, a certain amount of proportioning is obtained, but this type of regulation is less satisfactory than the boiler 70 control constituting our invention.

An object of this invention is to provide a method and a means for blowing down the boiler in accordance with the operating conditions.

Another object of this invention is to provide a method and a means for regulating the quality of the steam generated under varying conditions.

A further object is to provide a method and 80 a means for controlling the condition of the boiler water.

A still further object is to provide a method and a means whereby the amount of boiler blow-down is reduced to the minimum consistent 85 with securing a satisfactory quality of steam under varying operating conditions.

Boiler blow-down may be regulated by, and made proportionate to, the amount of water evaporated and the rate of evaporating 90 it. Since the boiler feed and the steam output both indicate the amount and rate of evaporation, it is possible to control the boiler blow-down by either one of these factors.

This method of control is satisfactory when 95 the water fed into the boiler is of substantially constant quality (that is contains an unvarying amount of substances in solution and suspension), and when there are no great variations in the load. This method 100

of control, which removes solid matter from the boiler at the rate it is fed in by the feed water, maintains a substantially constant boiler concentration. This method, however, 5 does not bring about a reduction in concentration for materially increased loads, nor does it permit an increase in concentration when the load is reduced which is desirable in order to secure the highest quality of steam 10 and at the same time reduce boiler blow-down to a minimum with a consequent saving of heat. When the load is increased to a point that is too high for the constant concentration fixed by the method of blow-down control described above, the steam generated 15 will tend to increase in moisture content.

It has become the practice to purify the steam leaving the boiler of entrained moisture or boiler water. This prevents the 20 steam from carrying moisture or boiler water with its highly concentrated impurities into the steam pipe lines, superheaters, engines, turbines and other steam plant equipment. By the use of such purified steam of high 25 quality, greater efficiency is secured, and clogging, erosion, and other similar troubles are avoided.

Usually a steam purifier is installed within the steam outlet drum of the boiler in place of 30 the so-called "dry" or collecting pipe. The moisture and impurities dissolved or suspended therein, are separated from the steam which must pass through the purifier to reach the steam outlet connection. The impurity 35 laden moisture, thus separated, is collected in a suitable lower part of the purifier housing from which it is conveyed by a pipe drain line to a steam trap or other discharge which is usually outside of the boiler. The steam 40 trap accumulates the moisture, and each time it becomes filled with the same, it effects a discharge.

A satisfactory steam purifier of this character is shown and described in the copending 45 application of Walter J. Hughes and others, Serial No. 188,104, filed May 2nd, 1927.

While in general a steam purifier collects and discharges to the trap more moisture as more steam is produced by the boiler, and less 50 moisture as less steam is produced by the boiler, it is apparent that the amount of water discharged by a steam purifier, and the rate of the discharge is a function of other variables also. Thus, if the quality of the 55 steam varies due to a greater or less turbulence in the boiler, which may be caused by a change in the steaming rate or of the concentration or of the boiler water level, more or less water will be collected and discharged 60 by the purifier. In this manner the amount of the steam purifier discharge and the rate of the discharge will be an indication of the general conditions of operation instead of any single element.

65 The purifier discharge, therefore, is an-

other means, besides the boiler feed and steam output, of controlling the blow-down of the boiler. The control of the boiler blow down by the purifier discharge is advantageous since it regulates the condition of 70 the boiler water by reducing the concentration of the boiler water for high loads and permitting increases in concentration for low loads. This method of blow-down control tends to compensate the boiler conditions 75 to the quality of the steam generated.

In the preferred purifier discharge control, means are provided for blowing down the boiler a fixed amount each time the steam purifier trap makes a discharge. The 80 amount of blow-down may be regulated by a valve or orifice to any desired amount; thus, if the trap makes a discharge for each gallon of accumulated moisture from the steam, the blow-down line actuated by the trap may 85 contain a valve or orifice set to provide escapement of 3 gallons, or any other amount, from the boiler at the same time and with the same frequency. Since the water collected in the purifier is practically all actual 90 boiler water the discharge of this water is in actuality a partial blow-down of boiler. This steam purifier discharge is alone seldom sufficient to afford an adequate blow-down, but it must be taken into consideration 95 as a part of the total boiler water removed. In the present example the total blow-down will be the combined discharge of the blow-down line and the steam trap which in this case is 4 gallons.

If the steam quality is say 99 percent, then the trap discharge represents a steam moisture content of 1 percent and the trap actuated blow-down represents three times this amount, making a total of 4 percent of the 100 steam output. Further, if the steam quality lowers due to a too high boiler water concentration, say to 98 percent, then the trap will discharge twice as often. Simultaneously, the trap actuated blow-down will be doubled and in effect a total blow-down of 8 percent is reached. Whenever this occurs fresh boiler feed water replaces the blow-down and so reduces the concentration that the reverse sequence takes place. Steam quality improves, less trap discharges take place, and there is proportionately less trap actuated blow-down. In this manner concentration of the boiler water is reduced automatically 110 until boiler steaming conditions quiet down to the production of high quality steam with which there is at the same time a reduced or compensated blow-down, etc.

When large quantities of moisture are separated by a steam purifier and discharged by a steam trap, it is economical to save the heat contained in this water. Such water has been heated to the temperature of the steam and contains as many heat units per pound 125 as the water in the boiler. For this purpose 130

a heat interchange is provided. This moisture or water discharged from the trap is passed through a closed type heater or heat interchanger before being run to waste. 5 Feed water passed through the heating elements of this heater on its way to the boiler takes up the heat, thus effecting the saving through heat interchange. It may also be desirable to combine the trap discharge and 10 the trap actuated blow-down causing them to pass together through a heat exchanger in which boiler feed water makes contact with the heating interchanging elements. Separate heat interchangers can be placed upon 15 the purifier discharge line and the blow-down line, and such heat interchangers could also be placed before the particular discharge means used, instead of after as shown.

The accompanying drawings show several 20 embodiments of the invention.

In the drawings:

Fig. 1 shows an arrangement by means of which the moisture collected in the steam purifier actuates an intermittent blow-down;

25 Fig. 2 shows a diagrammatical arrangement by means of which the moisture collected in the steam purifier actuates a continuous blow-down, and

Fig. 3 is a cross section taken along lines 30 3—3 of Figs. 1 and 2, and shows means for maintaining a substantially constant liquid level within the boiler which may be used in connection with the apparatus described herein.

35 In Fig. 1 boiler drum 11 is about half filled with water and contains the steam space 13. The impure steam from the steam space is drawn off through the purifiers 14 in which the entrained moisture and impurities are separated, and the purified steam then goes on through the steam nozzle 15, from whence it passes to a steam system. The collected moisture and impurities pass out of the purifier casing into the continuously slanting drain pipe 16 to a steam trap 17 outside of the boiler.

The steam trap 17 contains a ball float 18 to which is attached a rod 19, which moves a pivoted lug 20 having two fixed projecting pins 21. These fixed pins 21, when moved by the ball float 18, engage and move the trip weight 22 to either the left or the right, depending upon the level of the water in the chamber 17. Attached to the trip weight is 40 the cam 23 which actuates a bell crank lever 24. In the figure the trip weight is shown to the right depressing the horizontal arm of lever 24, which is its position when the collecting chamber is about to discharge or 45 discharging. The bell crank lever 24, when in this position, will pull the rod 25 to the left, opening the pilot valve 26, which will cause the admission of steam under boiler pressure to the lines 27 and 28, which will 50 result in a discharge from the steam trap 17

and from the water space 12 of the boiler in a manner which will be subsequently described. When the chamber 17 discharges and empties the ball float 18 will descend until the weight 22 passes the center position and falls to the left. This will cause the cam 23 to release instantly the horizontal arm of the bell crank lever 24, which will move the valve rod 25 to the right and quickly close the pilot valve 26. When the trap 17 fills again the reverse operation will take place. The ball float 18 will ascend until the trip weight 22 is moved past the center position by the pins 21, whereupon the trip weight will fall to the right again and will depress the horizontal arm of the bell crank lever 24, opening the pilot valve 26. 70 75 80

The steam under boiler pressure, admitted into lines 27 and 28 by the pilot valve 26, is conveyed to the cylinders of the valves 29 and 30, which open and close the boiler blow-down and steam trap discharge lines respectively. Since the areas of the pistons 31 and 32 are greater than the areas of the valves 33 and 34, when boiler pressure acts through the lines 27 and 28 against the pistons 31 and 32, the unbalanced effect causes opening of the valves 33 and 34 in a substantially instantaneous manner, compressing the springs 35 and 36 and providing free passage from 39 to 40 on the boiler blow-down line and from chamber of the steam trap 17 through the cage 42 to the discharge line 43. The moisture collected in the chamber 17 is thus quickly discharged by boiler pressure, and the boiler is blown down simultaneously a definite amount, which will be controlled by the boiler pressure in the shell 11 and the amount of time required for the ball float 18 to descend to the position at which the trip weight 22 will fall to the left, causing the valve 26 to close. The amount of blow-down through the line 37, 39 and 40 can be adjusted by the valve 38 or by an adjustable or replaceable orifice which can be inserted in the line 37 in place of, or in addition to, valve 38. 100 105 110

The illustration of the position of the valves 33 and 34 and the representation of the sizes of the pipes 40, 43 and 41 upon Fig. 1 is purely diagrammatic. When the valves 33 and 34 are open, the water will be discharged therethrough to atmospheric pressure. At all times the pressure in lines 40, 43 and 41 will be substantially atmospheric. 115 120

When the lowered level of water in the chamber 17 effects closure of the pilot valve 26 as described above, the steam under boiler pressure will be cut off from the pistons 31 and 32. Leakage around the pistons 31 and 32, together with the action of the compressed springs 35 and 36, will result in very rapid closure of the valves 33 and 34. The boiler pressure in the lines 37 and 16 assists 125 130

the springs 35 and 36 in closing the valves 33 and 34.

- It is desirable to have all valves described, of a type which open and close quickly, substantially as described herein, in order that wire-drawing which causes undue wear, may be avoided. Another desirable feature in the quick opening and closing of the valves, especially those which discharge water from the purifier and from the boiler blow-down connection, lies in the better proportionment of boiler blow-down to steam moisture content due to a more simultaneous action of the two.
- 15 The combined discharges from the boiler blow-down 40 and the steam purifier 43 are combined in the pipe 41 and flow through the closed type heat interchanger 44, where they give up their heat to the incoming feed water. They then flow to waste through the pipe 45. The feed water will enter the heat interchanger through pipe 46, and after having acquired the heat of the discharged water, will enter the water space of the boiler 20 through the pipe 47.

In case it is desired to directly operate the valve 29, such can be accomplished by closing the valve 48 and opening the valve 49, whereupon steam under boiler pressure will flow into the cylinder of the valve 29 from the upper part of the steam trap casing 17. In case it is desired to supplement or replace the boiler blow-down through the valve 29, such can be effected by operating the valves 30 35 50 and 51. The valve 50 will open the boiler blow-down line directly to waste.

- In Fig. 2 the steam purifier discharge flows down through the continuously sloping drain pipe system 16 into the steam trap 60. The steam trap 60 contains the vertically sliding dome element 61, under which the water discharge or the combined steam and water discharge from the steam purifier will be introduced by means of the pipe 16. The water discharge so introduced will pass from under the dome element 61 through the openings 62 upwardly through the outer part of the steam trap casing 63, and then past the valve 64, into the discharge line 68. When steam is discharged into the trap by the pipe 16, or when a mixture of steam and water is discharged into the trap 60 by the pipe 16, the steam will collect in the upper part of the dome structure 65 and will slowly leak out through the pin-hole opening 66 in the top of the dome and condense. The buoying effect of the steam will cause the dome 61 to rise in the steam trap casing, and this will close the valve 64 and prevent any further discharge from the steam trap. As the steam subsequently slowly leaks out through the pin-hole opening 66 and condenses, the dome 61 will again sink to the bottom of the steam trap casing, opening the valve 64 and again permitting

discharge into the line 68. The dome 61 is guided in its upward and downward motion in the steam trap casing by the projecting portions 67. The discharge from the line 68, which will be substantially constant under uniform operating conditions when the steam generated is of a constant quality, flows into the orifice box 69.

The water contained in this orifice box 69 will flow out through the adjustable or replaceable orifice 70 into the discharge pipe 71. The discharge box 69 constitutes one side of a balance structure having the pivoted beam 72, which has as the other side the orifice box 89 upon the boiler blow-down discharge line. The balance beam 72 is normally held in horizontal position through the vertical arm or rod 73, to which is attached the sliding weight 74 which can be set at any desired height thereon by the set screw 75. The stops 76 prevent the beam 72 from being tilted too far to the right or the left.

The movement of the balance causes the movement of the rod 79 through the link 78, which is attached to the balance structure by the pivot connection 77. The movement of the rod 79 operates a sliding valve in the pilot valve structure 80 so as to open a connection between the line 81, to which water is being supplied under pressure, and either the line 82 or 83, which will cause such water under pressure to be supplied to either the upper end or the lower end of the cylinder 84, causing a movement of the piston 85. This movement regulates the amount of opening of valve 86 which is upon the boiler blow-down line 87.

When larger quantities of water are discharged into the orifice box 69, the balance will tilt down to the left. This will actuate the pilot valve 80 in such a manner that the water under pressure from the line 81 passes into the line 83, raising the piston 85 and in turn further opening the valve 86. The water contained in the upper part of the cylinder 84 will be discharged to the line 82 through the pilot valve 80 to the line 88. This will permit an increase in the continuous discharge through the valve 86 until the concentration of the boiler water has been reduced to such a degree that the steam quality returns to its normal value.

When less moisture is discharged by the steam purifier, the balance structure will then tilt to the right with the result that the pilot valve 80 will be so operated, that water under pressure will be admitted from the line 81 to the line 82 and from thence into the upper part of the cylinder 84, causing downward movement of the piston 85. At the same time, the water contained in the lower part of the cylinder 84 will pass out through the pipe 83 through the pilot valve 80 to the line 88.

The apparatus should be so arranged, and

the orifices 70 and 90 should be so adjusted that when a steam of desired quality, say 98 percent, is generated and passed through the steam purifier, sufficient water will be discharged through the lines 68 and 87 into the orifice boxes 69 and 89 respectively, so that the balance structure will be in an equilibrium or balanced condition. When it is desired to supplement the boiler blow-down through the line 87, or when it is desired to replace the boiler blow-down through the valve 86, such can be done by operation of the valves 92 and 93.

To illustrate the method of operation in Fig. 1 when the load is constant with substantially constant quality feed water and constant steam quality, a boiler having the following characteristics may be taken:

Constant feed of 6,000 gallons per hour, containing ten grains of solid per gallon.

Steam quality to be maintained—98 percent (that is, moisture content of steam—2 percent)

Constant solid content not to be exceeded—250 grains per gallon.

Trap set to discharge every 2 gallons of separated moisture.

If the steam is considered to be produced as rapidly as the water is fed in, the trap will discharge once every minute. Since approximately 100 gallons of water will be vaporized and removed as 98 percent steam every minute, 1,000 grains of solids will be fed in during the same interval. Since the discharge from the trap will only remove 500 grains of solids, it is desirable to blow-down the boiler simultaneously an amount of 2 gallons to make up the other 500 grains. This blow-down is controlled by the operation of the steam trap 17 and the boiler pressure, and can be varied by the adjusting valve 38.

If the load on the boiler suddenly increases, the quality of the steam will decrease and its moisture content will increase. The solid content of 250 grains per gallon would be too high for the production of steam of 98 percent quality so that it is necessary to reduce the solid content of the boiler water. If the quality of the steam decreases to 96 percent, due to such a load variation, twice the quantity of water will be separated in the purifier and the total discharge of steam trap and blow-down will amount to 8 gallons per minute instead of 4, and an increased discharge will continue until the solid content of the boiler water had been reduced to such a value that 98 percent steam is produced.

Such a decrease in the steam quality may also be caused by an increase in the solid content of the feed water. In such a case the steam trap with its controlled blow-down will be discharged more frequently with the result that the boiler water concentration

will be maintained at such a value that the desired steam quality will be attained.

The operation of the arrangement shown in Fig. 2 is very similar in principle to the operation of the apparatus of Fig. 1. When it is desired to maintain a constant steam quality of 98 per cent, the orifices 70 and 90 can be set so as to continually discharge the desired amount of water. If the desired steam quality is 98 per cent and the feed and amount of steam evaporation is as is stated above the orifice 70 will be of such a size and shape as to discharge two gallons of moisture every minute under a predetermined head in the orifice box 69. If, at the same time, it is also necessary to discharge 2 gallons of water from the boiler blow-down, the orifice 90 will also be of such a size and shape as to obtain this desired amount of blow-down. In any case, the orifices 70 and 90 and orifice chambers 69 and 89 are so proportioned that, when the steam of the desired quality is being produced by the boiler, the amount of water in orifice chambers 69 and 89 will substantially balance each other. A continuous blow-down of this character is very advantageous inasmuch as all changes in boiler operating conditions take place almost imperceptibly.

A constant level may be maintained in the boilers shown and described in connection with each of the modifications disclosed heretofore by a device such as shown in Fig. 3, for example. As shown, this device may comprise a vertical pipe 200 integral with pipe 47 in the modification shown in Fig. 1, and with pipe 87 in the modification shown in Fig. 2. This vertical pipe connects through horizontal pipe 201 with the inlet 202. Liquid level chamber 203 contains float 204 which actuates valve 205 in horizontal inlet pipe 201 by means of levers 206, 207 and 208. When the liquid level within the boiler and chamber decreases the float is lowered, thereby operating to open the valve 205 to allow additional water to flow into the boiler to restore the normal level. If the level within the boiler exceeds a predetermined value the float is raised, thereby closing the valve 205.

To one skilled in the art, many variations of our invention will occur upon a reading of the foregoing specific description, and such modifications coming within the spirit of our invention are intended to be included in the appended claims. Thus we have in mind that in many cases it will be advantageous to have the steam purifier in the steam line outside the boiler instead of in the steam space as illustrated.

What is claimed is:

1. In a boiler control apparatus, a steam purifier, a steam trap, means for conducting collected moisture from the steam purifier to the steam trap, a blow-down for the boiler actuated by discharge of said trap and an adjusting means for regulating the amount

- of the blow-down for each discharge of said trap.
2. In a boiler control apparatus, a steam purifier, discharge means for the impurities collected by said purifier, a blow-down for the boiler operated by said discharge means.
3. In a boiler control apparatus, a steam purifier, a steam trap exterior to the boiler, a means for conducting collected moisture from said purifier to said trap and means actuated by said trap for periodically blowing down the boiler.
4. In a boiler control apparatus, a steam purifier, a steam trap, means for conducting collected moisture from said purifier to said trap, means actuated by said trap for periodically blowing down the boiler, and heat interchanging means for the boiler feed water and the purifier discharge.
5. In a boiler control apparatus, a steam purifier, a steam trap, a means for conducting water collected in said purifier to said trap, means actuated by said trap for periodically blowing down the boiler, means for combining the trap discharge and the boiler blow-down and means for heat interchanging the combined discharge and the boiler feed water.
6. An apparatus for regulating the condition of boiler water, which comprises a steam purifier, means for discharging said steam purifier means actuated by the amount of the water discharged from said purifier for removing suitable quantities of boiler water, and means for recovering the heat in such discharged water.
7. The method of regulating boiler conditions which comprises removing moisture from the steam produced, and regulating the amount of blow-down from the water space in proportion to the amount of water obtained from the steam.
8. An apparatus for regulating the quality of steam, which comprises means affected by the quantity of steam output from a boiler, means for discharging water from said boiler, means adapted to remove suitable quantities of boiler water by said discharging means, and cooperating means actuated by said first mentioned means adapted to operate said last mentioned means.
9. An apparatus for regulating the condition of boiler water which comprises a steam purifier, means for discharging said steam purifier, means for discharging the boiler, and means responsive to the amount of water discharged from said purifier for removing suitable quantities of boiler water by said boiler discharging means.
10. An apparatus for regulating the condition of boiler water comprising means responsive to the quality of the steam generated by said boiler, a blowdown line from said boiler, a valve upon said blowdown line, and means actuated from said first mentioned means for actuating said valve.
11. An apparatus for regulating the quality of steam generated in a boiler, comprising means responsive to the quality and quantity of the steam generated by said boiler, a blow-down line from said boiler, a valve upon said blowdown line, and means actuated by said first mentioned means for actuating said valve.
12. A boiler control apparatus which comprises a means for separating the moisture in steam, a collecting chamber for said moisture, a blowdown line to said boiler, and means associated with the separated moisture in said collecting chamber adapted to open and close said blowdown line.
13. In a boiler control apparatus, a boiler shell containing a steam space in the upper portion thereof, a steam purifier in the steam space of said boiler shell, a means of admitting steam to said purifier, a conduit for removing purified steam from said purifier and conveying it to the steam outlet of the boiler, a conduit for draining the impurities to without the boiler shell and a boiler blow-down means outside of the boiler actuated by said drainage.
14. In a boiler control apparatus, a boiler shell, a valved blowdown line from said boiler shell, and a means for maintaining the steam quality constant comprising a means for removing the moisture from the steam, a collecting chamber for the separated moisture, a float in such chamber, and a means actuated by said float adapted to discharge said chamber and to open and close the valve on the blow-down line.
15. In a boiler control apparatus, a boiler shell, a blowdown line from said boiler shell, a piston operated valve upon said blowdown line and a means for maintaining the steam quality constant comprising a steam purifier in the steam space of said boiler shell, a float chamber without said boiler shell, a drain line from said purifier to said float chamber, a pressure fluid line to said above mentioned piston operated valve, and a valve upon said fluid pressure line actuated by the movement of the float in said float chamber.
16. In a boiler control apparatus, a boiler shell, a blowdown line from said boiler shell, a piston operated valve upon said blowdown line, and a means for maintaining the steam quality constant comprising a steam purifier in the steam space of said boiler shell, a float chamber without said boiler shell, a drain line from said purifier to said float chamber, a discharge line from said float chamber, a piston operated valve upon said discharge line, a pressure fluid line to said above mentioned piston operated valves, and a valve upon said fluid pressure line actuated by the movement of the float in said float chamber.
17. In an apparatus for regulating the quality of steam, means responsive to the steam output from the boiler comprising a

steam purifier in the boiler shell through which the steam from said boiler must pass, a chamber adapted to collect the separated moisture from said purifier, means to discharge said chamber, and means actuated in coordination with said last named means to remove suitable quantities of boiler water.

18. An apparatus for producing steam of constant quality comprising a boiler, a steam purifier, a means of discharging said purifier, a chamber for receiving said discharge, means for discharging said chamber, and means associated with said last mentioned means for blowing down the boiler.

19. The method of regulating boiler conditions which comprises appraising both the quantity and quality of the steam generated by the boiler by separating the moisture therefrom, and controlling the quality of the steam by blowing down the boiler in proportion to the moisture separated.

20. The method of regulating boiler conditions which comprises separating the mois-

ture from the steam generated by the boiler, and maintaining a constant quality steam by utilizing a higher boiler concentration when smaller amounts of moisture than normal are being separated per unit time.

21. In a boiler controlling apparatus, a steam purifier, a steam trap, means for conducting collected moisture from the steam purifier to the steam trap, a blowdown for the boiler, and means in association with the discharge of said trap for actuating said blowdown.

22. In the operation of a boiler, the process which comprises passing steam generated by the boiler through a purifier separating the water from said purifier, and regulating the boiler blowdown in accordance with the amount of water separated from said purifier.

In testimony whereof we have hereunto subscribed our names.

WALTER J. HUGHES.
